REFRIGERATOR AND TRAY CONSTRUCTION

Enoch Swedman, St. Paul, Minn., assignor to
 Seeger Refrigerator Company, St. Paul, Minn.,
 a corporation of Minnesota

Application March 14, 1942, Serial No. 434,658

4 Claims. (Cl. 312—150)

My invention relates to an improvement in refrigerator and tray construction, wherein it is desired to provide a novel type of tray and tray support for mechanical refrigerators.

It has become common practice to support a tray beneath the evaporator unit of a mechanical refrigerator for the storage of foods and other products which are to be maintained at a low temperature. As the tray is positioned directly beneath the evaporator unit, a low temperature is maintained within the tray. Furthermore, such a tray may be used to catch moisture which may drip from the evaporator unit during defrosting of the unit.

The object of the present invention is to provide a novel type of tray and support therefor, so as to prevent accidental removal of the tray. In order to gain access to the contents of the tray it is desirable that the tray slide outwardly from beneath the unit. I have found that from time to time trays of usual construction will be pulled entirely out of their supporting slides, often allowing the contents of the trays to spill, or allowing an entire tray to drop.

It is an object of the present invention to provide a pair of opposed slides slidably engaging the flanged edge of the tray so that the tray may be pulled forwardly from its normal position immediately beneath the refrigerator unit. Cooperating means are provided on the flanged tray edge and on the supporting slides to limit outward movement of the tray. Thus, after the tray has moved forwardly a predetermined distance, the cooperating means will engage to lock the tray from further outward movement.

A further object of the present invention resides in the provision of a simple release, whereby the cooperable means locking the tray from outward movement may be disengaged to permit complete removal of the tray when it is so desired. The weight of the tray and of the contents thereof normally hold the cooperable means on the tray and slide in engagement. By the simple expedient of lifting the forward end of the tray, however, the cooperable means may be disengaged and the tray entirely removed.

While the structure defined relates particularly to a tray positioned directly beneath the evaporator unit of the refrigerator, the same arrangement may be used for supporting a hydrator or vegetable tray in some other portion of the refrigerator, without materially changing the principles of the invention.

It is a feature of the present invention to provide a tray having a pair of oppositely disposed

outwardly extending flanges cooperable with a slide supported within the body of the refrigerator. The flange of the tray is provided with notch means in each flange which terminates in a shoulder spaced from the rear edge of the tray. This shoulder cooperates with an inwardly turned ear or stop shoulder formed as a part of each slide. When the tray is drawn forwardly in the slide until the shoulder in the flange engages the ear or stop shoulder on the slide, the tray is held from further outward movement. By lifting the forward end of the tray, however, the shoulder of each tray flange is disengaged from the corresponding stop on the slides to permit complete removal of the tray.

These and other objects and novel features of my invention will be more clearly and fully set forth in the following specification and claims.

In the drawings forming a part of my specification:

Figure 1 is a front elevational view of the upper portion of a refrigerator showing the tray supported beneath the evaporator unit of the refrigerator.

Figure 2 is a plan view of the tray and the supporting shelf therefor.

Figure 3 is a perspective view of a detail portion of the supporting shelf and slide structure, also showing a portion of the tray supported thereby.

Figure 4 is a side elevational view of a portion of the tray flange showing a notch and stop shoulder formed therein.

Figure 5 is a central cross-sectional view through the supporting shelf and slide construction, the position of the section being indicated by the line 5—5 of Figure 2, but showing the tray removed.

Figure 6 is a view similar to Figure 5, showing the tray in place upon the supporting slides.

Figure 7 is a view similar to Figure 6 showing the tray in partially removed position.

Figure 8 is a sectional view through the slide and through the rim of a tray showing a modified form of tray flange construction.

Figure 9 is a side elevation view of the top portion of the tray illustrated in Figure 8.

Figure 10 is a perspective view of a modified for mof stop which may be used on the supporting slides.

The cabinet 10 of the refrigerator A is provided with a door opening 11, which may normally be closed by a door 12 hingedly secured to the cabinet 10 by hinges 13. An evaporator unit B is mounted within the cabinet and in the particular

type of refrigerator illustrated this unit is located centrally between the sides of the cabinet. The location of the unit B is of no importance in the present invention.

A shelf C is mounted within the refrigerator cabinet 10 and is supported by any suitable means. In the particular construction illustrated, supporting pins such as 14, indicated in Figure 5 of the drawings, support the shelf C, the pins 14 being mounted on the side walls of the refrigerator cabinet 10. A stop shoulder 15 engages the forward pin 14 to prevent accidental outward movement of the shelf C, while a hook-shaped bracket 16 extends around and beneath the rear pin 14 so as to prevent the rear end of the shelf from tilting upwardly. The manner of supporting the shelf C forms no part of the present invention.

The shelf C, in the form of construction illustrated, comprises a substantially U-shaped frame rod 17 which extends along the side walls and rear wall of the refrigerator cabinet. A pair of frame rods 19 extend in parallel relation to the opposed sides 20 of the frame 17 and in spaced relation thereto. The forward portions 21 of the frame rods 19 are laterally offset to widen the space therebetween to facilitate insertion and withdrawal of the tray. The forward ends of the frame rods 19 are connected to the forward ends of the opposed sides 20 of the frame member 17 by transversely extending connecting members 22. A series of parallel shelf rods 23 connect the rear member 24 of the frame 17 to the transversely extending connecting members 22 to form a support for food or other products within the refrigerator.

A shelf is thus formed which is generally U-shaped in plan and which has an open central section to accommodate the tray D. The manner in which the tray is supported will now be described.

As best seen in Figures 3, 5, 6, and 7 of the drawings, a pair of inverted U-shaped supports 25 are mounted upon the frame rods 19. The supports 25 include a substantial horizontally extending portion 26 which extends parallel to and is spaced directly above the frame rods 19; and downturned supporting ends 27 which are welded or otherwise secured to the frame rods 19. The horizontal portions 26 of the supports 25 act to support the flanged edge 29 of the tray D, the lower surface of the flanged edges 29 resting upon the horizontal portions 26.

Secured to the supports 25 and extending along the length of the horizontal portions 26, I provide angle members 30. These angle members 30 are welded or otherwise affixed to the portions 26 of the supports 25 and extend upwardly from the outer surfaces thereof. The flange 31 of each of the angles 30 extends horizontally over the portion 26 of each support 25 to form a track between the upper surface of the supports 25 and the under surface of the respective flange 31. The flanges 31 extend over the side flanges 29 of the tray D, so as to prevent the tray from being lifted vertically off the supports 25. The flange 31 is spaced somewhat above the flange 29 of the tray, however, to permit limited vertical movement for a purpose which will be later described.

Each of the angles 30 extend forwardly beyond the downturned supporting end 27 of each support 25. Adjacent the forward end of each of the angles 30, I provide an inturned ear 32 designed to engage the undersurface of a flange 29 on the tray D. Each ear 32 is slightly above the level of

the adjacent support 25 so that the forward end of the tray D is supported by the ears 32. These ears 32 cooperate to form a stop for limiting forward movement of the tray, as will now be described.

In Figure 4 of the drawings, I disclose a side elevation view of a portion of the flange 29 of the tray D. A notch 33 is formed in the lower surface 34 of the flange 29. This notch 33 is formed with a sloping or inclined surface 35 at its forward extremity and is formed with a shoulder 36 at its opposite end. As the tray D is slid forwardly on its supporting tracks, the ears 32 engage the lower surface 34 of the flange 29 to support the forward end of the tray. When the tray is moved forwardly a sufficient distance, the ears 32 slide into the notches 33, which are in opposed relation on opposite side flanges 29. The shoulder 36 at the extreme end of the notch 33 engages against the inner end 37 of the corresponding ear 32, thus preventing further forward movement of the tray. Thus outward movement of the tray will be limited by the cooperation of the ears 32 and the shoulder 36 of the notch 33.

If it is desired to entirely remove the tray D from the refrigerator, it is only necessary to elevate the forward end of the tray D until the shoulder 36 is raised above the level of the ears 32, whereupon outward movement of the tray may be continued. The flange 31 is spaced above its corresponding support 25 sufficiently to permit disengagement of the shoulder 36 from each ear 32.

In Figures 8, 9, and 10 of the drawings, I disclose a modified form of construction which operates in a manner similar to the construction previously described. In this form of construction the frame rods 40 correspond to the frame rods 19, and the supports 41 corresponds with the supports 25. The supports 41 are provided with a horizontally extending portion 42 substantially parallel to the frame rods 40 and connected thereto by downwardly turned supporting ends 43, corresponding to the connecting ends 27. The lower extremity of the ends 43 of the supports 41 are welded or otherwise affixed to the frame rods 40.

Angles 44, similar to the angles 30, are welded or otherwise secured to the outer edges of the supports 41. A horizontal flange 45 on each angle 44 extends above and in spaced relation to the horizontal portion 42 of the supports 41. The angles 44 extend forwardly from the supports 41 and are provided with inturned ears 46 designed to extend beneath the flange of the tray.

Each of the ears 46 is either above the level of the upper surface of the supports 41 or else is provided with a shoulder 47 formed therein, as best illustrated in Figures 8 and 10 of the drawings. This shoulder 47 is designed to cooperate with the tray to limit the outward sliding thereof.

The tray E, used in conjunction with the supporting structure illustrated in Figures 8 and 10, is similar or identical to the tray D in general shape and form. A pair of transversely extending side flanges 49 extend outwardly from the body 50 of the tray. This tray is provided with a relatively thin flange portion 51 at the forward end of the tray. A shoulder 53 is provided between the flange portions 51 and 52. This shoulder 53 is designed to engage the shoulder 47 on the ear 46 to limit outward movement of the tray as it is pulled forwardly. Obviously by lifting the forward end of the tray until the shoulder 53 is raised above the level of the shoulder 47, the forward movement of the tray may be continued, if it

is desired, to entirely withdraw the tray from the refrigerator.

The construction illustrated in Figures 8, 9, and 10 of the drawings is advantageous over the first described construction in that the lower surface of the flange 49 rides flat along the surface of the supports 41. In the construction first described the rear end of the flange 29 rides upon the surface of the supports 25, while the forward portion of the flange 29 is raised above the surface of the supports 25 by the ears 32. While the shoulder construction 47 has been shown in conjunction with the tray E, it is obvious that the tray D could be similarly used with this type of stop shoulder. Similarly the tray E could be used in conjunction with the ears 32 without departing from the spirit of this invention.

In accordance with the patent statutes, I have described the principles of construction and operation of my refrigerator and tray construction, and while I have endeavored to set forth the best embodiments thereof, I desire to have it understood that obvious changes may be made within the scope of the following claims, without departing from the spirit of my invention.

I claim:

1. The combination with a slidable tray and a pair of tray supporting spaced tracks at the sides thereof, of an outwardly projecting flange on each tray side, one of said flanges having shoulder means therein intermediate the ends thereof, the spaced tracks each comprising an upwardly bowed inverted U-shaped support upon which said tray flanges may slide, an angular guide secured to one vertical side of the base of said inverted U-shaped support, said angular guide including a flange extending horizontally in spaced relation to the upper surface of said base, and an inwardly turned ear on said angular member above the level of the upper surface of said base engageable with said shoulder upon slid- able movement of the tray in one direction.

2. The combination with a slidable tray and a pair of tray supporting spaced tracks at the sides thereof, of an outwardly projecting flange on each tray side including substantially right angular shoulder means, said tracks each comprising a substantially horizontally extending bar, a right

angular angle member secured to one vertical surface of said bar, and projecting forwardly therefrom, said angle member including a flange in spaced horizontal relation to the upper surface of said bar, said bar and angle member forming a channel designed to receive a flange of the tray, and an ear in said angle member projecting horizontally above the level of said bar and forwardly therefrom to engage against said shoulder to limit relative slidable movement therebetween in one direction when said tray is held by gravity against said ear.

3. The combination with a slidable tray and a pair of tray supporting spaced tracks at the sides thereof, of an outwardly projecting flange on each tray side, one of the flanges having shoulder means therein intermediate the ends thereof, the spaced tracks each comprising a rod upon which said tray flanges may slide, an angular guide secured to one vertical side of said rod, said angular guide including a flange extending horizontally in spaced relation to the upper surface of said rod, and an inwardly turned ear on said angular member above the level of the upper surface of said rod engageable with said shoulder means upon slidable movement of the tray in one direction.

4. The combination with a slidable tray and a pair of tray supporting spaced tracks at the sides thereof, of an outwardly projecting flange on each tray side including substantially right angular shoulder means, said tracks each comprising a substantially horizontally extending bar, a right angular member secured to one vertical surface of said bar, and projecting forwardly therefrom, said angle member including a flange in spaced horizontal relation to the upper surface of said bar, said bar and angle member forming a channel designed to receive a flange of the tray, an ear on said angle member projecting horizontally at approximately the level of said bar and forwardly therefrom, and projecting means on said ear extending above the level of said bar and designed to engage against said shoulder means to limit relatively slidable movement therebetween in one direction when said tray is held by gravity against said ear.

ENOCH SWEDMAN.
